RAYMOND L. WARD, OF KANSAS CITY, MISSOURI, ASSIGNOR OF ONE-HALF TO BESSIE N. JOHNSON, OF KANSAS CITY, MISSOURI.

SHEET-HOLDDOWN ATTACHMENT FOR FLY-STICKS.

1,115,629.

Specification of Letters Patent.

Patented Nov. 3, 1914.

Application filed June 8, 1914. Serial No. 843,598.

To all whom it may concern:

Be it known that I, RAYMOND L. WARD, a citizen of the United States, residing at Kansas City, in the county of Jackson and 5 State of Missouri, have invented certain new and useful Improvements in Sheet-Hold-down Attachments for Fly-Sticks, of which the following is a specification.

This invention relates to sheet hold-down 10 attachments for fly sticks for flat bed printing presses, and has for its object to produce a simple, effective and inexpensive means for imposing sufficient pressure upon each sheet laid down or stacked by the fly sticks 15 to prevent the sheet adhering to the sticks, as the latter start to swing back to their original positions, so that the joggers may engage and arrange the sheet in proper position upon the table or the sheets previously stacked thereon.

To this end the invention consists in certain novel and peculiar features of construction and organization as hereinafter described and claimed; and in order that it 25 may be fully understood, reference is to be had to the accompanying drawing, in which:—

Figure 1, is a vertical section of a printing press showing the sheet receiving table 30 and joggers and the fly sticks, and traveling tapes for disposing printed sheets upon the fly sticks. Fig. 2, is a top plan view of the right hand half of Fig. 1. Fig. 3, is an enlarged section on the line III—III of Fig. 35 1. Fig. 4, is a sectional view of a bracket forming a part of each fly stick attachment.

In the said drawing, where like reference characters identify corresponding parts, 1 is 40 a table and 2 the joggers thereon, the mechanism for operating the joggers being omitted as forming no part of the subject matter of this application.

3 are the customary fly sticks secured 45 upon rock shaft 4, and arranged between adjacent fly sticks in the usual manner are the endless traveling tapes 5 for conveying the printed sheets from the press proper down upon the fly sticks, 6 indicating the 50 wheels over which the tapes run near the pivoted ends of the fly sticks, and 7 is the shaft upon which such wheels are mounted; all of the parts thus far described being of common and well known construction.

Upon each or as many of the fly sticks as 55 desired, I provide sheet hold-down attachments each being preferably constructed as follows: 8 is a bracket fitting slidingly upon a fly stick and provided with a threaded opening 9 wherein is mounted a clamping 60 screw 10 for impingement upon the underside of the fly stick to secure the bracket at the desired point thereon, and said bracket is provided with a pair of parallel perforated ears 11 in which are secured a pivot 65 12 for a substantially V-shaped swinging frame. This frame comprises a pair of arms 13 and 14, the former having an eye 15 pivotally engaging the pivot 12. The arm 14 is provided with a longitudinal slot 70 16 receiving the fly stick, as shown clearly. In the preferred construction this swinging frame will preferably be made from a piece of wire bent at one end to form the eye mentioned and then bent at its opposite end 75 to form the slot 16, the extremity of the end of the wire forming the slot being bent around the wire at the junction of arms 13 and 14 thereof.

Assuming that the parts are in the position shown by full lines Fig. 1, and that a sheet of paper has been carried by the tapes over the fly sticks, it will be seen that said sticks, as they swing upwardly, will lift such sheet of paper from the tapes and carry it 80 over and deposit it upon the table or on one or more sheets stacked thereon, the fly sticks moving with such rapidity that the swinging frames remain in the same relative position to the fly sticks in which they are shown in 85 full lines Fig. 1, that is to say the fly sticks swing with such rapidity that the said frames cannot swing ahead of them. The fly sticks swing to substantially a horizontal 90 position and in effect lay the sheet flatly 95 down upon the table or underlying stack, and this is accomplished while the joggers are withdrawn from the sides of the stack so that each sheet stacked will be placed between the joggers. Usually considerable 100 trouble is encountered due to the fact that each sheet stacked by the fly sticks adheres more or less to the sticks and is raised by the latter as they start to swing back to their original position, the sheets, after the sticks 105 have moved upward a few inches on their return movement, dropping back and frequently falling upon the joggers which at

such time have started to move inward for the purpose of disposing said sheet with its edges flush with the edges of the stack of sheets which have previously been properly arranged by the joggers. If a sheet drops down upon the joggers it must be instantly stacked or thrown aside by hand, as otherwise it will be impossible to stack the next sheet and those which follow it.

10 Where my sheet hold-down attachments are employed, they rest upon each sheet placed upon the table or stack of sheets, and retain such position until the fly sticks have traveled back in their return movement the 15 full length of the slots 16, by which time the sheet last stacked will have become completely disengaged from the fly sticks. As the fly sticks continue their return movement they carry the swinging frames with 20 them, and after the fly sticks have attained their original positions the swinging frames swing downward to their original positions, so as to offer no obstruction to the placing of the next printed sheet upon the fly sticks.

25 For sheets of different size the attachments will be placed at different points of adjustment along the fly sticks and for extremely large sheets the positions of the attachments upon the sticks may be reversed, 30 that is to say, the blocks 8 may be secured upon and near the outer ends of the sticks with the swinging frames projecting inwardly therefrom or toward the shaft 4.

From the above description it will be apparent that I have produced sheet hold-down attachments for fly sticks for printing presses which operate efficiently and reliably and which obviously may be modified in minor particulars without departing 35 from the principle of construction involved or sacrificing any of the advantages of the appended claims.

Copies of this patent may be obtained for five cents each, by addressing the "Commissioner of Patents, Washington, D. C."

I claim:—

1. The combination with a fly stick, of a frame pivotally carried by and adapted to swing in the same plane as the fly stick and both with and independently thereof; said frame embodying portions lying in the same vertical plane as and adapted for engagement with the fly stick for limiting independent pivotal movement of the frame with respect to the fly stick.
2. The combination with a fly stick, of a sheet hold-down attachment comprising a bracket adjustable on the fly stick, and a substantially V-shaped frame pivoted to the bracket and adapted for movement in a vertical plane, one arm of the V-shaped frame having a slot through which the fly stick loosely extends.
3. The combination with a fly stick, of a paper hold-down attachment, comprising a bracket adjustable upon the fly stick, and a swinging frame comprising a rod bent to form two arms extending at an angle to each other, one end of the rod being doubled to form a slot extending longitudinally of and for the full length of said arm; said slot receiving the fly stick.
4. In a sheet hold-down attachment for fly sticks, a swinging frame of V-shape in side view, one arm of the V-shaped frame having a longitudinal slot for its full length and the other arm terminating at its free end in an eye.

In testimony whereof, I affix my signature in presence of two witnesses.

RAYMOND L. WARD.
